UNITED STATES PATENT OFFICE.

JAMES M. H. JACOBS, OF DAYTON, OHIO, ASSIGNOR TO THE MUTUAL FURNITURE MANUFACTURING COMPANY, OF MIAMISBURG, OHIO, A CORPORATION OF OHIO.

STEPLADDER.

Application filed February 15, 1922. Serial No. 536,628.

To all whom it may concern:

Be it known that I, JAMES M. H. JACOBS, a citizen of the United States, residing at Dayton, in the county of Montgomery and 5 State of Ohio, have invented certain new and useful Improvements in Stepladders, of which the following is a specification, reference being had therein to the accompanying drawing.

10 This invention relates to step ladders and similar structures and is in the nature of an improvement on the structure shown and described in the application filed June 6, 1921, by B. E. Willett, Serial No. 475,299.

15 One object of the invention is to provide such a structure which will be simple in construction and of a strong, durable character; and which will be rigidly supported in its extended position.

20 A further object of the invention is to provide such a structure which may be readily folded into a compact form; and which when folded will stand upon the front frame.

Other objects of the invention will appear as the structure is described in detail.

25 In the accompanying drawings Fig. 1 is a front elevation of the ladder in its extended position; Fig. 2 is a side elevation of the same; Fig. 3 is a side elevation of the 30 ladder in its folded position; Fig. 4 is a sectional view taken on the line 4—4 of Fig. 2; and Fig. 5 is a side elevation of the upper portion of the ladder partly broken away.

35 In these drawings I have illustrated one embodiment of my invention and have shown the same as comprising a front or step frame, consisting of side members 1 connected one to the other by steps 2 and

40 truss rods 3 which also serve to reinforce the steps. The uppermost step 4 is in the present instance mounted on the upper ends of the side members 1 and is secured thereto by angle irons 5 and reinforced by braces 6.

45 The rear frame member also consists of two side members 7 connected one to the other by tie rods 8 and braced one against the other by diagonal braces 9. The upper ends of the side members 7 are connected by a cross bar 50 10 which rests upon the same and is connected thereto by angle irons 11.

It will be noted that the rear frame is of a height considerably greater than the front frame and that the upper end of the front

frame is spaced a considerable distance from 55 the rear frame. The front frame is connected with the rear frame by means of spacing devices each of which consists of two members, the front member 12 being pivotally connected at its front end with 60 the upper portion of the front frame and the rear member 13 being pivotally connected at its rear end with the rear frame. The two members are pivotally connected 65 one to the other, as shown at 14, and are provided with means for limiting their downward movement and thus rigidly supporting the same when the structure is in 70 its extended position. In the present device the two members 12 and 13 of each connecting device are formed of angle irons so arranged that one flange of the angle iron will extend inwardly from the lower edge of the other flanges, thus forming a laterally extending flange which also serves to support a 75 platform. The horizontal flange 15 of the front member 12 is cut away at both ends to permit the necessary movement of this member with relation to the parts with 80 which it is connected. The forward end of 85 the rear member 13 extends beyond the pivotal connection 14 and overlaps the adjacent end of the horizontal flange 15 of the front member 12, thus forming a positive stop which limits the downward movement of the 90 two parts. The connecting devices are further reinforced and braced by diagonal bars 16 which are pivotally connected at their upper ends with the rear members 13 of the respective connecting devices and are 95 pivotally connected at their lower ends with the respective side members of the front frame.

A platform is interposed between the 100 upper portion of the front frame and the rear frame, upon which the occupant of the ladder may stand, and in order that this platform may be folded into a compact position when the ladder as a whole is folded I have formed this platform of two parts 17 and 18 which are supported respectively by the horizontal flanges of the front and rear members of the two connecting devices. The front part 17 of the platform is preferably 105 permanently secured to the front members of the spacing devices but in the present construction I have shown the rear member 18 as loosely mounted upon the rear mem-

bers 13 of the spacing devices and connected thereto by links 19 so that it may be moved into the elevated position shown in Fig. 5. The ends of the rear part 18 of the platform 5 are reinforced by metal bars having hook shaped ends 20 which engage over one of the connecting rods 8 of the rear frame. The construction and operation of this movable platform are the same as shown in the above 10 mentioned application of Willett and, therefore, need not be here described in detail.

It is desirable that guards should be provided at the sides of the platform and, in the structure here shown, I have provided 15 at each side of the platform a guard 21 in the form of a curved rod which is pivotally connected at its upper end to the upper portion of the rear frame, as shown at 22, and is pivotally connected at its lower end to 20 the upper portion of the front frame. This latter connection is preferably formed by mounting the guard upon the pivot pin 25 by means of which the front member 12 of the 25 spacing device is connected with the front frame, this pin extending outwardly far enough to receive the guard. This enables the two parts to be pivotally mounted on the same axis and facilitates the folding of the structure into a compact form. The lower 30 ends of the guards, as shown at 23, extend beyond their points of pivotal connection with the frame and are arranged to engage the respective side members 1 and brace the guards against lateral strain, thus to a large 35 measure relieving the pivotal connections of this strain. As here shown, the side members 1 of the front frame are provided with metal plates 24 with which the lower ends of the guards may contact, thereby 40 forcing the construction and preventing any wear of the side members 1 by contact with the guards.

It will be apparent from the foregoing description that I have provided a very simple structure which is of a strong, durable 45 character and which, when in its extended position will be firmly supported and can not collapse or fold when occupied. The spacing devices which support the platform 50 are of a strong, rigid character, and are firmly braced against downward movement when the ladder is in its extended position, but are so constructed and arranged that when the two frames of the ladder are moved 55 one toward the other these spacing devices will fold one toward the other into the position shown in Fig. 3, this being accomplished by the mere movement of the frames. Moreover, the guard rods 21 will also move into 60 a position extending lengthwise of the frames so that the folded structure is very compact. It will be noted that when the frames are moved one toward the other the rear frame will move upwardly, thereby 65 causing the folded structure to be support-

ed solely by the front frame and enabling the same to stand against a wall when it is desired to be used as a ladder when in its folded position.

While I have shown and described one embodiment of my invention I wish it to be understood that I do not desire to be limited to the details thereof as various modifications may occur to a person skilled in the art.

Having now fully described my invention what I claim as new and desire to secure by Letters Patent, is:

1. In a structure of the character described, a front frame, a rear frame to support said front frame, said front frame being of less height than the rear frame and having its upper end spaced from said rear frame, spacing devices for said frames, each comprising a front member and a rear member pivotally connected one to the other and pivotally connected respectively with the upper portion of the front frame and with said rear frame, means to limit the downward movement of the intermediate portions of said members, and a platform comprising separate parts carried respectively by the front and rear members of said spacing devices.

2. In a structure of the character described, a front frame, a rear frame to support said front frame, said front frame being of less height than the rear frame and having its upper end spaced from said rear frame, spacing devices for said frames, each comprising a front member and a rear member pivotally connected one to the other and pivotally connected respectively with the upper portion of the front frame and with said rear frame, and a platform comprising separate parts carried respectively by the front and rear members of said spacing devices, one of said members having a part extending beyond its point of connection with the other member and engaging said other member to limit the downward movement of said platform.

3. In a structure of the character described, a front frame, a rear frame to support said front frame, said front frame being of less height than the rear frame and having its upper end spaced from said rear frame, spacing devices for said frames each comprising a front member and a rear member pivotally connected one to the other and pivotally connected respectively with the upper portion of the front frame and with said rear frame, one of said members having a flange extending laterally from the lower edge thereof and having its ends spaced from the respective ends of said member, the other of said members having a portion extending beyond its point of connection with the first mentioned member and overlapping the adjacent end of said flange, and a plat-

form comprising two parts supported respectively by the front and rear members of said spacing devices.

4. In a structure of the character described, a front frame, a rear frame to support said front frame, said front frame being of less height than the rear frame and having its upper end spaced from said rear frame, spacing devices for said frames each 10 comprising a front member and a rear member pivotally connected one to the other and pivotally connected respectively with the upper portion of the front frame and with said rear frame, one of said members having 15 a flange extending laterally from the lower edge thereof and having its ends spaced from the respective ends of said member, the other of said members having a portion extending beyond its point of connection with the first mentioned member and overlapping the adjacent end of said flange, and a platform comprising two parts supported respectively by the front and rear members of said spacing devices, and a 20 brace pivotally connected with the last mentioned member and with the frame with which the first mentioned member is connected.

5. In a structure of the character described, a front frame, a rear frame to support said front frame, said front frame being of less height than the rear frame and having its upper end spaced from said rear frame, a platform extending between the 30 upper portion of said front frame and said rear frame and comprising front and rear parts pivotally connected one to the other and to the respective frames, and means to limit the downward movement of said platform about said pivotal connections, and guards arranged at the sides of said platform and each pivotally connected on fixed axes with said front and rear frames.

6. In a structure of the character described, a front frame, a rear frame to support said front frame, said front frame being of less height than the rear frame and having its upper end spaced from said rear frame, spacing devices for said frames, each 40 comprising a front member and a rear member pivotally connected one to the other and pivotally connected respectively with the upper portion of the front frame and with said rear frame, a platform comprising 50 separate parts carried respectively by the front and rear members of said spacing devices, one of said members having a part extending beyond its point of connection with the other member and engaging said other

member to limit the downward movement of 60 said platform, and guards arranged at the sides of said platform and each pivotally connected on fixed axes with the upper portions of the respective frames.

7. In a structure of the character described, a front frame, a rear frame to support said front frame, said front frame being of less height than the rear frame and having its upper end spaced from said rear frame, spacing devices for said frames, each 70 comprising a front member and a rear member pivotally connected one to the other and pivotally connected respectively with the upper portion of the front frame and with said rear frame, a platform comprising 75 separate parts carried respectively by the front and rear members of said spacing devices, one of said members having a part extending beyond its point of connection with the other member and engaging said other 80 member to limit the downward movement of said platform, and guards arranged at the sides of said platform and each pivotally connected on fixed axes with the upper portions of the respective frames, and each having 85 a portion extending below its point of connection with said front frame and forming a brace for the guard.

8. In a structure of the character described, a front frame, a rear frame to support said front frame, said front frame being of less height than said rear frame and having its upper end spaced from said rear frame, foldable platform supporting devices connected with said front and rear frames 95 and spacing the same one from the other, and guards pivotally connected on fixed axes with said front and rear frames.

9. In a structure of the character described, a front frame, a rear frame to support said front frame, said front frame being of less height than said rear frame and having its upper end spaced from said rear frame, spacing devices connecting said front and rear frames, and each comprising 100 two parts pivotally connected one to the other and pivotally connected with the respective frames, a platform carried by said spacing devices, and guards arranged at the sides of said platform and each pivotally connected at its upper end with said rear frame and each pivotally connected at its lower end with said front frame on an axis coincident with the axis of the adjacent spacing member.

In testimony whereof, I affix my signature hereto.

JAMES M. H. JACOBS.
